UNITED STATES PATENT OFFICE

96,553

DESIGN FOR A WATCH HOLDER

Ellison S. Irelan, Elgin, Ill., assignor to Illinois
Watch Case Company, Elgin, Ill., a corporation of Illinois

Application January 18, 1935, Serial No. 54,911

Term of patent 7 years

To all whom it may concern:

Be it known that I, Ellison S. Irelan, a citizen of the United States, residing at Elgin, in the county of Kane and State of Illinois, have invented a new, original, and ornamental Design for a Watch Holder, of which the following is a specification, reference being had to the accompanying drawing, forming part thereof, in which the figure is a view in perspective of a watch holder showing my new design, a dominant feature of which is the configuration and ornamentation applied to the apertured supporting plate.

I claim:

The ornamental design for a watch holder, as shown and described.

ELLISON S. IRELAN.
